UNITED STATES PATENT OFFICE.

CHARLES G. MYERS, OF CLEVELAND, OHIO.

LIGHT CONCENTRATOR AND PROJECTOR.

1,042,716.

Specification of Letters Patent. Patented Oct. 29, 1912.

Application filed January 7, 1912. Serial No. 522,887.

To all whom it may concern:

Be it known that I, CHARLES G. MYERS, a citizen of the United States, residing at Cleveland, in the county of Cuyahoga and State of Ohio, have invented certain new and useful Improvements in Light Concentrators and Projectors, of which the following is a specification.

My invention relates to improvements in light concentrators and projectors, and is particularly designed for the use of dentists, surgeons, opticians, and the like, in their operations, the primary object of the invention being to provide a generally improved device of this class for use in connection with any suitable and convenient source of illumination whereby the rays of light may be concentrated and projected or directed upon any particular point or portion being operated upon.

A further object of the invention is to provide a device for use in connection with a light of great power and brilliancy which may be readily and conveniently brought into use when desired without in any way disturbing the patient or interfering with the operations of the operator.

With the above mentioned ends in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Figure 1, is a side elevation of the improved concentrator and projector as it appears in connection with an ordinary "Nernst" lamp. Fig. 2, an enlarged longitudinal sectional view of the same, detached. Fig. 3, a view showing a modified form of mounting and supporting the same. Fig. 4, a perspective view of the method of mounting and supporting the same from the arm of a dental or surgical chair, this being the preferred form. Fig. 5, a further modification, the supporting stem being secured in a bracket mounted upon a wall or other stationary object. Fig. 6, a perspective view of the protecting shield detached from the lamp body.

Similar numerals of reference designate like parts throughout all the figures of the drawings.

The improved concentrator and projector is adapted for use in connection with any suitable and convenient source of illumination, preferably one of great power and brilliancy, such as a gas or electric lamp, the present embodiment showing its use in connection with a Nernst lamp 1, particularly adapted for use in dental and surgical operations, as illustrated in Fig. 1, of the accompanying drawings.

The improved concentrator and projector comprises a housing or lamp body portion 2, adapted to be secured to the form of the lamp used, said housing or lamp body portion 2, in the present instance, being open at its rear end and adapted to have its marginal edges 2^a, slip over the front off-set marginal edges 1^a of the Nernst lamp body 1. When used in connection with a lamp of this character the housing or lamp body portion 2, should be provided with a plurality of openings as at 3, thus forming an open housing or main body portion for the purpose of ventilation and the like.

As a means for shielding or protecting the eyes of the operator from the direct rays of the light arising from the source of illumination, as well as throwing a diffused light downwardly upon the operator's instrument carrying table, an adjustable shield 5, is mounted upon the housing or body portion 2, said shield being secured and clamped thereon by means of the clamping ring 6.

As a means for adjusting and supporting the improved concentrator and projector, a flexible holder 7, of a well understood construction is provided, said flexible holder being provided at its ends with exteriorly threaded stem-heads 8, one of said heads being secured to the housing or body portion 2, in the present instance, by means of a threaded stud or projection 9, and the other in a threaded opening of a supporting stem or bar 10. The supporting stem or bar 10, is adapted to be vertically adjusted and secured by means of any suitable and convenient supporting means such as the supporting-stand 11, as shown in Fig. 3, or the

supporting bracket 12, shown in Fig. 5. The preferable means, however, for supporting and adjusting the supporting-stem or bar 10, is shown in Fig. 4, of the drawings, and comprises a stationary bracket 13, secured upon one of the arms 14, of the dental or surgical chair, said bracket 13, being provided at its end with a clamping-head 15, and a clamping thumb-screw or bolt 16.

10 The form of mounting just described and illustrated in Fig. 4, of the drawings is preferable for the very obvious reason that it eliminates the necessity for adjusting or changing the supporting means with every 15 movement or adjustment of the dental or surgical chair since the stationary bracket 13, follows the movements of the chair and therefore brings the concentrator or projector into the same relative position with respect to the patient after being once 20 adjusted.

The housing or main body portion 2, is provided at its front with a projecting tube 17, carrying a pair of projecting or lens tubes 18. Each tube 18, is provided at one end with a double-convex lens 19, said tubes being oppositely arranged with their open or opposite ends telescoping so that the lenses 19, may be moved to and from each other 25 for the purpose of regulating the concentration and projection of the rays of light as desired. One of the tubes 18, has its lens end slidably mounted in the projecting tube 17, whereby the lens 19, carried thereby may 30 be moved to and from the source of illumination as desired for the purpose of contributing to the function above stated with respect to the relative movement of the lenses 19, carried in the lens tubes 18.

From the foregoing description, taken in connection with the accompanying drawings, the operation and advantages of my invention will be readily understood.

Having thus described my invention, what I claim and desire to secure by Letters Patent is,—

1. A light concentrator and projector, comprising a source of illumination, an open lamp housing provided with an adjustable shield, an adjustably mounted flexible holder therefor, and projecting tubes having telescoping open ends and each provided with a lens at the opposite end, one of said tubes having its lens end connected to said open lamp housing.

2. A light concentrator and projector, comprising a source of illumination, a main body portion provided with a projecting tube, a flexible adjusting and supporting holder, and oppositely disposed lens-tubes having telescoping open ends, one of said tubes being slidably mounted in said projecting tube and provided with a lens in close proximity to said source of illumination.

3. A light concentrator and projector, comprising a source of illumination, a main body portion provided with a projecting tube, a flexible holder for adjusting and holding said main body portion, a projecting tube having one end slidably mounted in said first mentioned projecting tube and provided with a lens, and a third projecting tube slidably mounted in said second tube and provided at its front end with an objective-lens.

4. A light concentrator and projector, comprising a source of illumination, an open lamp body therefor, an adjustably mounted holder, an adjustable shield on said lamp body, and projecting tubes each provided with a double-convex lens at one end and having their open ends telescoping, one of said tubes having its lens ends slidably and adjustably connected to said open lamp body.

5. A light-concentrator and projector, comprising a source of illumination, a ventilated projecting tube detachably connected to said source of illumination and provided with a projecting shield above and a lens in front of the latter, an adjustably mounted supporting holder, and a second tube having one end slidably mounted in said first mentioned projecting tube and provided at its front with an objective lens.

6. A light-concentrator and projector, comprising a source of illumination, a main body portion having a light emitting open portion below said source of illumination and provided with a projecting tube, a lens in said projecting tube in close proximity to said source of illumination, and a second projecting tube having one end slidably mounted in said first mentioned projecting tube and provided at its front with an objective lens.

7. A light-concentrator and projector, comprising a source of illumination, a ventilated lamp body having a protecting shield above and a light diffusing open portion below said source of illumination, a condensing lens in front of said source of illumination, and a projecting tube provided with an objective lens and movable relative to said condensing lens.

8. A light-concentrator and projector, comprising a source of illumination, a main body portion having a light emitting opening below said source of illumination, and provided with a projecting tube, and lenses located in said tube.

9. A light-concentrator and projector, including a cylindrical section forming a projecting tube and carrying a lens therein and formed with a projecting hood at one end projecting beyond said lens, said hood being open at its bottom, a source of illumination supported beneath the hood in alignment

with the lens, and an objective carrying section telescopically adjustable into the first named section.

10. A light-concentrator and projector, comprising a source of illumination, a main body portion provided with a protecting hood above and a light emitting open portion below said source of illumination, a projecting tube provided with a lens in close

proximity to said source of illumination, 10 and an objective lens at the outer or front end of said projecting tube.

In testimony whereof I have affixed my signature, in presence of two witnesses.

CHARLES G. MYERS
